United States Patent Office.

L. P. WILCOX, OF BROOKLYN, NEW YORK.

Letters Patent No. 66,434, dated July 2, 1867.

IMPROVEMENT IN MODE OF ATTACHING TOOLS TO THEIR HANDLES.

The Schedule referred to in these Letters Patent and making part of the same.

TO ALL WHOM IT MAY CONCERN:

Be it known that I, L. P. WILCOX, of Brooklyn, E. D., in the county of Kings, and State of New York, have invented a new and improved Tool-Handle; and I do hereby declare that the following is a full, clear, and exact description of the same, reference being had to the accompanying drawings, making a portion of this specification, in which—

Figure 1 is a side view of a tool-handle constructed according to my invention.

Figure 2 is a longitudinal section of the same, taken at right angles to fig. 1.

Similar letters of reference indicate corresponding parts in both figures.

This invention consists in the combination of a sliding compressing ferrule, with a wooden or other handle divided longitudinally for a portion of its length, and furnished with a central longitudinal slot or cavity, whereby the chisel, file, or other tool may be very conveniently and securely attached to the handle, and at the same time be capable of being readily detached or removed therefrom when required.

To enable others to understand the construction and operation of my invention, I will proceed to describe it with reference to the drawings.

The handle proper is shown at A, and may be of wood or other suitable material, and for the most part of any desired or appropriate form, but with a portion at one end thereof made tapering, as shown at *a* in the drawings. Formed centrally within this handle A, and extending from the extremity of the tapering portion *a* nearly to the opposite end of the handle, is a longitudinal slot or cavity, *b*, which may be of circular or cylindrical form, and which is designed to receive the shank of the chisel, file, or other tool, as will hereinafter be fully set forth. The tapering portion *a*, and also that part of the handle immediately behind such tapering portion thereof, is divided longitudinally by a narrow slit, *c*, which extends entirely through the handle, as indicated more clearly in fig. 2, and which intersects the central slot or cavity *b*. The ferrule is represented at B, and is made of any desired length, and of a tapering form, with its interior corresponding in shape and size to the outer or smaller part of the tapering portion *a* of the handle A, in such manner that when the ferrule B is driven back upon the aforesaid tapering portion *a*, it will compress the same, narrowing the slit *c*, and diminishing the diameter of the outermost end of the slot or cavity *b*, or, in other words, forcing toward each other the two opposite sides of the longitudinally-divided tapering portion *a* just mentioned.

The shank of the file or chisel is inserted in the slot or cavity *b*, as indicated in red outline in fig. 2, with some little space between its extremity and the inner end of the aforesaid slot, in order that any possibility of splitting the handle A may be avoided. The ferrule B is then forced or driven back upon the tapering portion *a*, and compressing the said portion, as hereinbefore explained, causes the shank of the tool to be firmly gripped or clamped between the two opposite sides of the aforesaid portion *a*, and thus rigidly secures the tool in the handle. When it is desired to detach the tool from the handle, the ferrule B is simply driven forward upon the portion *a*, which being thus relieved from the compressing action of the ferrule, expands and releases its hold upon the shank of the tool. The shank of the tool is thus grasped or held within the handle when the ferrule is moved or slid inward, and released when such ferrule is moved or slid outward. Instead of a single slit, *c*, the tapering portion of the handle may be divided by two or more similar slits situated in a position radial to the central slot *b* of the said handle, the action of the sliding ferrule B, in compressing or releasing the aforesaid tapering portion of the handle, being the same as when a single slit, extending entirely through the handle from side to side, as hereinbefore fully described, is employed.

I am aware that brad-awls and similar tools have been provided with expanding holders forming shanks to be inserted in wooden handles, as in the patent of H. Hemenway, September 4, 1828; these therefore I do not claim, but what I claim as new, and desire to secure by Letters Patent, is—

The wood stock or handle A, constructed with its one end *a* tapering and slotted longitudinally as at *c*, in combination with the tapering sliding ferrule B, substantially as and for the purpose set forth.

L. P. WILCOX.
